CHARLES R. PEDDLE, OF TERRE HAUTE, INDIANA.

Letters Patent No. 61,860, dated February 5, 1867.

IMPROVED PNEUMATIC BRAKE FOR RAILROAD CARS.

The Schedule referred to in these Letters Patent and making part of the same.

TO ALL WHOM IT MAY CONCERN:

REISSUED

Be it known that I, CHARLES R. PEDDLE, of Terre Haute, in the county of Vigo, and State of Indiana, have invented a new and improved Pneumatic Brake for Railroad Cars; and I do hereby declare that the following is a full, clear, and exact description thereof, which will enable others skilled in the art to make and use the same, reference being had to the accompanying drawings, forming part of this specification, in which—

Figure 1 is a side view of a locomotive and a side sectional view of a car, taken in the line $z z$, fig. 2, having my invention applied to them.

Figure 2, a plan or top view of the same.

Figure 3, an enlarged detached vertical section of the means by which the power is applied to the brakes.

Figure 4, an enlarged detached vertical section of the steam chest and cylinder of a locomotive.

Similar letters of reference indicate like parts.

This invention relates to a new and improved means for operating the brakes of railroad cars by compressed air forced into the air cylinders underneath the cars, by the locomotive, without any essential modification of the working parts of the latter, a valve and air pipe being simply connected to the steam chest of the steam cylinder. The object of the invention is to obtain a simple and economical means for operating simultaneously the brakes of all the cars of a train, and placing the brakes under the complete control of the engineer.

A represents a locomotive; B one of the steam cylinders thereof, and C the steam chest. These parts may be constructed and arranged in the ordinary manner, and therefore do not require a special description. On the top of the steam chest C there is a tube, D, to which a pipe, E, is attached, and within the tube D there is a valve, F, by which the pipe E may be made to communicate with the steam chest, or be cut off therefrom when desired. G G represent the trucks of a car attached to the locomotive by any suitable or approved coupling, and H is a pipe which is secured in a longitudinal position under the bottom or bed I of the car body, the pipe H being connected by a flexible tube, J, with the pipe E, so that said pipes E H may communicate with each other, and due allowance made for the variation in the length of space between the locomotive and car, under the draught movement of the same, and due allowance also made for lateral play of the cars and locomotive. K is a cylinder, secured in a vertical position at the centre of the bed or bottom I of the car, and having a piston, L, fitted within it, the rod M of said piston passing down through the lower end of cylinder K, and having a lever, N, pivoted centrally to its lower end, as shown clearly in figs. 1 and 3. To each end of the lever N there is connected, by a pivot, α , a rod, O, the upper ends of which are pivoted to one end of right-angular levers P P, the fulcrum β of which are on the car bed or bottom I. The opposite ends of the levers P are connected by rods $c c$ to levers Q Q, one end of which has the ordinary hand-brake chains R attached, and the opposite ends connected by rods $d d$ to brake levers S attached to the outer shoe bars T, the lower ends of the levers S being connected by rods $e e$ to the inner shoe bars T'. (See fig. 1.) All the cars of a train are supplied with the parts above described, and their pipes H connected by flexible tubes.

The operation is as follows: When the train is in motion, and it is desired to stop, the engineer shuts off the steam, and opens the valve F in the top of the steam chest C, and reverses the motion of the slide valve U in the steam chest C; by this means air is drawn into cylinder B through the exhaust passage f, the piston g, in the steam cylinder B, working, of course, under the momentum of the locomotive, and air forced through the steam chest C into the pipe E, and thence into pipe H, (see red arrows,) and the piston L in the air cylinder K raised under the pressure of the air. With the piston L the lever N is also of course raised, and the levers P P actuated, and the brakes applied, as will be readily seen. This arrangement, it will be seen, not only causes the train to be stopped by the application of the brakes, but also by a back pressure on the pistons g, and the invention admits of the brakes being applied by hand in the usual way whenever required.

Having thus described my invention, I claim as new, and desire to secure by Letters Patent—

The combination of the steam cylinders, steam pipes, and steam chests of a locomotive with air pipes E H, extending the whole length of a train of cars, the valves F in the steam chests, and the air cylinders K, provided with pistons L, connected with the brake mechanism of the cars, to operate in the manner substantially as and for the purpose set forth.

I also claim the lever N connected to the rod M of piston L, and to the bent or right-angular levers P P, to which the rods $c c$ of the levers Q are connected, for the purpose of transmitting the power to the brakes, substantially as shown and described.

CHARLES R. PEDDLE.
